UNITED STATES PATENT OFFICE.

JUSTIN M. ST. JOHN, OF CEDAR RAPIDS, IOWA.

WEEDER.

1,328,063.

Specification of Letters Patent. Patented Jan. 13, 1920.

Application filed June 21, 1917. Serial No. 175,990.

To all whom it may concern:

Be it known that I, JUSTIN M. ST. JOHN, a citizen of the United States, residing at Cedar Rapids, in the county of Linn and 5 State of Iowa, have invented certain new and useful Improvements in Weeder; and I do hereby declare the following to be a full, clear, and exact description of the invention, such as will enable others skilled 10 in the art to which it appertains to make and use the same.

This invention relates to implements for the pulling of weeds and has for its object to produce a weeder of very simple and in- 15 expensive construction, which is adapted to easily and rapidly extract such weeds as dandelion, plantain, and the like, removing the whole root, and but little of the adjacent soil.

20 The nature of the invention is fully disclosed in the description and claims following, reference being had to the accompanying drawings, in which:—

Figure 1 is a front view of a weeder em- 25 bodying the invention, in position for use. Fig. 2 is a side view of the same, in weed- holding position. Fig. 3 is a view in perspective, showing a simple type of ejector. Fig. 4 is a section through the handle, show- 30 ing the top of the head, with the foot bracket attached to the head and handle. Fig. 5 is a section in a vertical plane through the middle of the head and bracket. Figs. 6 and 7 are sections diagonal to the 35 head, and showing both straight and in- curved prongs. Figs. 8 and 9 are bottom views of the figures just above them.

To a wooden handle 1, which both for lightness and cheapness is preferred to 40 metal, is attached the working head of the tool. In practice this is formed of a square of sheet metal 2, pierced equidistantly at three or more points, preferably four, to receive as many prongs 3. These may be 45 ordinary wire spikes, those known as 16-penny being well suited to the purpose. The heads of these spikes are held in place by folding over two opposite corners 4 of the squares, as shown in Fig. 4. One cor- 50 ner is folded back to an oblique position, as shown at 5, and serves as a slight brace for the head as attached to the handle, as well as to give a finished appearance to the back side of the head. To the other, flat

corner 6, is riveted a right-angled bracket 55 7, which serves as one of the principal means for attaching the head to the handle, and as a foot-piece, when foot pressure on the tool is required. The head is also secured to the handle by a wood-screw 8, as 60 shown in Fig. 5. As hung in the head the spikes may move freely in any direction except endwise.

Attached to a suitable push-rod, which will be described presently, is a foot-plate 65 9, pierced to receive the prongs, but with shorter spaces between the holes than are those of the head, so that normally, with the foot at the lower ends of the prongs, in working position, as shown in Fig. 1, the 70 prongs converge somewhat. The foot-plate is secured rigidly to a push-rod 10, of which Fig. 3 is one of the simplest type, being a loop of stout wire, outturned at 11 for a hand-piece, and clenched at 12 through 75 holes in the foot-plate. This serves the purpose very well, if the tool be used with care, and is inexpensive in manufacture, being attached slidably to the sides of the handle by staples, as indicated. But as the 80 prongs may swing freely in any direction, the push-rod must also serve as their sole support against lateral movement, and a still more objectionable tendency to twist. The type of push-rod shown in Figs. 1 and 85 2 is therefore preferred in practice. This is the hardware stock known as "half-oval," and has the desired stiffness edge- wise, and is also strong enough in the other direction for all practical purposes. This 90 is riveted fast to the foot-plate, two rivets being used, to positively prevent any twist of the plate. The body of the push-rod may pass through notches 13 or holes 14 in the head, and also be held slidably under 95 ears 15 of a band 16 attached to the handle. Or wide staples may be used, as they have been in actual manufacture. Part way up the handle the side members of the rod are shown riveted to a sleeve 17 free to slide 100 on the handle. The sleeve serves for the convenient connection of a light spring 18, whose other end may be attached adjustably to the lower part of the handle, as to staples 19. The upper end of the long leg 105 of the push-rod might end as a simple hand-piece, as does the push-rod shown in Fig. 3, and this ordinarily serves very well for a

direct hand-piece by which to eject the weed. In actual service, however, it has been found practically necessary to provide leverage for the initial movement in ejecting the weed. It will sometimes happen that a large, tough root will be caught by the prongs and gripped so tightly that the foot-plate can only be started from its frictional position by either a smart blow or 10 forcible pressure on the push-rod. The latter is supplied by a short hand-lever 20, whose foot is mounted to run on a stirrup 21 attached to the handle. Once started, the movement of the ejector is easy. In 15 Fig. 2 the lever is shown in position for starting, which may be done with little pressure on the hand-lever. The tilt of the lever is limited in both directions, a loop or shoulder 22 of the push-rod abutting at 20 23 in one position, and at 24 in the other. When the latter takes place the lever of course slides along the stirrup.

It is to be noted that the spring 18 is a mere auxiliary to the manual operation of 25 ejecting the weed. To depend upon a spring to overcome the frictional grip of the foot-plate on the prongs is regarded as impractical, since experiment has shown that in some cases a pressure of from 30 to 40 30 pounds is required to release this grip, and to overcome this pressure each time in weeding is to impose too much labor on the operator. As the tool herein described is manufactured, the light spring is dispensed 35 with, its only practical use being to throw the ejector after being manually started, so the operator need not move the hand so far in the ejecting operation. To that extent its action is very satisfactory, but as no 40 catch for the push-rod in gripping position is needed or desired, the presence of the spring would cause trouble unless the operator were careful each time to push down hard enough to overcome its tension by the 45 frictional grip of the foot-plate. This is needless in light weeding, for under all conditions, and whether the working push be light or heavy, the frictional grip may be depended upon to hold the fingers (prongs) 50 converged, and thus prevent the escape of the inclosed root.

It is also regarded as important that the fingers be stiff. If made flexible, their elasticity must be overcome at each operation, 55 and unless the spring of the fingers be very stiff they will not grip the root hard enough to extract it, in some cases. The loosely mounted, stiff fingers operate with certainty and great ease, and equally well with small 60 and large roots.

It is desirable that the free ends of the prongs or fingers converge to as small a space as possible, so as to leave no central orifice for the escape of very small roots. 65 For this purpose cylindrical fingers are

found to be best, since they draw together very closely, as shown in Fig. 9. By making two of the fingers long and the other pair short, as shown in Fig. 6 both pairs will close tightly together, as indicated in Fig. 8. 70

By forming the fingers with incurves, as 75 shown in Fig. 7, a somewhat longer grip on the root may be obtained, the construction being better adapted for small than for large roots.

Unless the ground be very dry and hard the foot bracket is not needed, the tool working very easily, and the pressure of one hand being ordinarily sufficient. The bracket cannot well be dispensed with, however, and its presence makes it possible for the operator to overdo the pressure, which has a tendency to force the prongs together with a twist, lapping past each other at the points. This is not only bad for the tool, 85 but is apt to permit the escape sidewise of the root sought to be pulled. To prevent this the movement of the foot-plate on the prongs is limited by a stop 25, so located as to permit the points of the prongs to fully 90 converge radially, but not to cross each other.

Having thus described my invention, I claim:

1. A weeder, comprising a head, a series 95 of prongs mounted loosely therein, a foot-plate cooperating with the prongs and head to converge the points of the prongs as they are projected through said plate, and a guide for said foot-plate.

2. A weeder, comprising a head, a series of 100 rigid prongs mounted loosely therein, a foot-plate through which the prongs project at a converging angle, and means adapted to guide the foot-plate axially with respect to the head.

3. A weeder, comprising a head, a series 105 of rigid prongs mounted loosely therein, a foot-plate through which the prongs project at a converging angle, and means adapted to guide the foot-plate axially with respect to the head, and without rotary motion, whereby the prongs are caused to converge in radial planes, as described.

4. In a weeder, the combination of a head, 115 a series of prongs mounted loosely therein, a foot-plate pierced to receive said prongs, and a guide for the foot-plate, the bearings for the prongs in the head being spaced larger than those of the foot-plate.

5. In a weeder having a handle, head, 120 connected prongs normally converging downwardly, a foot-plate slideable thereon, and a connected push-rod, a hand-lever connected with the push-rod, and having a limited pivotal movement thereon, and a stirrup attached to the handle, and forming a slide-bearing and terminal stops for said lever.

6. In a weeder, the combination of a handle, head, connected, loosely hung prongs, 130

a foot-plate holding the prongs in normally converging position, and slideable along them, a manually operable push-rod connected with the foot-plate and adapted to prevent axial rotation thereof, and a stop to limit the upward movement of the foot-plate.

In testimony whereof I affix my signature in presence of two witnesses.

JUSTIN M. ST. JOHN.
